UNITED STATES PATENT OFFICE

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK

SUBMARINE SIGNALING

Application filed December 29, 1919. Serial No. 348,107.

This invention relates to submarine signaling and more particularly to a vibration responsive device adapted to be submerged under water for detaching or receiving vibrations set up in the water by submarine signaling apparatus or by the movement of a submarine vessel.

Various types of detecting devices employing diaphragms have been proposed for use under water in which a diaphragm is arranged to be set in vibration by sound waves imparted to the water by submerged sound signaling apparatus or by the action of the propeller or the movement of a vessel through the water. Such devices, however, have been open to the objection that unless some compensating device is provided, the hydrostatic pressure acting on the diaphragm when the device is submerged is sufficient to bow the diaphragm inward and destroy the adjustment of the apparatus if an electromagnetic unit is used, and in addition, to cause packing if a unit of the microphonic type is employed. With such devices, trouble has also been experienced due to the danger of destroying the sensitive adjustment necessary unless the apparatus is handled with extreme care.

It is the object of the present invention to provide a vibration responsive device so arranged that the adjustment or sensitiveness of the apparatus will not be impaired as a result of the hydrostatic pressure acting upon the diaphragm when the device is submerged and also arranged so that extreme care need not be exercised in handling the apparatus.

To accomplish these objects in accordance with a feature of this invention, the translating device which is connected directly to the center of the diaphragm and may be of either the electromagnetic or the microphonic type is pivotally mounted approximately through its center of mass.

This and other features of the invention may be more clearly understood by reference to the accompanying drawing in which Fig. 1 is a sectional view of a detecting device embodying the features of this invention and Fig. 2 is a sectional view along the lines 2—2 of Fig. 1 looking in the direction of the small arrows.

Referring to the drawing, there is provided a cup-shaped casing 5 having a flanged portion 6, against which an end plate 7 and diaphragm 8 are securely clamped by means of a clamping ring 9, the various parts being 55 clamped together by means of the bolts 10 and nuts 11. A gasket 12 of soft rubber or similar material is located, as shown, between the flanged portion 6 and end plate 7, and a similar gasket 13 is located between the end plate 7 and diaphragm 8, these gaskets being provided to prevent the entrance of water within the casing. The center of end plate 7 is provided with a perforation 14 and extending therethrough is a rod 15, one end of which is secured to the center of the diaphragm while the other end is rigidly secured to the end of armature 16 of an electromagnetic unit. This electromagnetic unit comprises a plurality of E-shaped punchings 17 which are securely clamped together between the side plates 18 and 19 by means of the screws 20—20, a pair of spacer blocks 21—21 being provided, as shown, to provide space for the coils 22—22 upon which are located the operating windings 32—32 and the polarizing windings 33—33. The armature 16 is resiliently supported at its central point by means of the spring 23, the ends of which are rigidly fastened to the side plates 18 and 19. The 80 end plate 7 is provided with a pair of right-angled extension members 24—24 on which the electromagnetic unit is adapted to be pivotally mounted. These members are provided with threaded openings from which 85 extend the trunnion screws 25—25, the ends of which are tapered, as shown, and adapted to engage the ball-bearings 26—26 located in the side plates 18 and 19. Lock nuts 27—27 are provided to hold the trunnion screws in 90 position when once adjusted satisfactorily. Projections 28—28 are provided on the side plates 18 and 19 to limit the amount of rotation of the electromagnet by serving as stops to engage the end plate 7. At the back of casing 5, a boss 29 is provided which is internally threaded to engage similar threads in the pipe 30 which is used for suspending the apparatus in position. The conductors 95 31—31 are led through the pipe 30, one pair 100

extending to the terminals of the operating windings 32-32 and the other pair extending to the terminals of the polarizing windings 33-33.

5. Vibrations of the diaphragm 8 cause corresponding movements of armature 16 and, with current flowing through the windings 33-33 corresponding variations are set up in the current flowing through the windings 10 32-32. Since the electromagnetic unit itself is pivotally mounted, any change in hydrostatic pressure which tends to bow the diaphragm inward or outward will tend to rotate the electromagnet about the trunnion 15 screws 25-25 and will not affect the space relation between the armature 16 and the core portions of the coils 22. However, vibrations of the diaphragm 8 in response to vibrations in the water resulting from submarine 20 signaling apparatus or the movements of a submarine vessel are of comparatively high frequency and will cause corresponding movement of the armature 16 without causing rotation of the electromagnetic unit itself. Since this unit is pivotally mounted approximately through its center of mass, there is little danger of loss of adjustment due to careless handling. The space between the projections 28-28 and the end 25 plate 7 is great enough to allow the unit to rotate freely in response to the bowing of the diaphragm under the maximum conditions to be expected in service.

What is claimed is:

35. 1. A translating device for sound wave energy comprising an inertia member including an electro-magnetic device; a diaphragm; means connecting said diaphragm to said inertia member, said connecting 40 means comprising an armature and resilient means supporting said armature on said inertia member and in operative relation to said electro-magnetic device; a mounting, and means rotatably supporting said inertia member on said mounting and for movement in a fixed path with said diaphragm.

50. 2. A translating device for sound wave energy comprising an inertia member including an electro-magnetic device; a diaphragm; means connecting said diaphragm to said inertia member, said connecting means comprising an armature and resilient means supporting said armature on said inertia member and in operative relation to said electro-magnetic device; a mounting, means rotatably supporting said inertia member on said mounting and means for limiting the rotation of said inertia member.

60. 3. A translating device for sound wave energy comprising an inertia member including a magnet, a diaphragm; means connecting said diaphragm to said inertia member, said connecting means comprising an armature and resilient means supporting said

armature on said inertia member and in biased relation to said magnet; a mounting, and means pivotally supporting said inertia member on said mounting the axis of the pivots passing through the center of mass 70 of said inertia member.

4. A translating device for sound wave energy, a casing including a diaphragm as one wall thereof; inertia means including means to vary the conditions in an electrical 75 circuit, means connecting said diaphragm to said circuit varying means, said connecting means including a vibratory member and resilient means for supporting said member in biased relation to said inertia means; and means rotatably supporting said inertia means on said casing for movement relative thereto and with the center of said diaphragm at all times.

5. In a device for the transmission of sound wave energy comprising a casing including as a wall portion a diaphragm; means in said casing for converting vibrating movements into electrical current variations including an electro-responsive device; 90 a member movable relative thereto including means mounting the latter for movement and for resiliently biasing it with respect to the former; means rotatably mounting said converting means on said casing for movement with the center of said diaphragm in a fixed path and means connecting said converting means with the diaphragm including the mounting and biasing means of the movable member of the electro-responsive device and 100 a rigid connection between said member and the diaphragm; said converting means and the means connecting the diaphragm thereto including inertia means.

In witness whereof, I hereunto subscribe my name this 20th day of December A. D., 1919.

HENRY C. HARRISON.
